UNITED STATES PATENT OFFICE.

NILS H. ANDERSON, OF MIDDLETOWN, CONNECTICUT, ASSIGNOR TO THE NOISELESS TYPEWRITER COMPANY, OF MIDDLETOWN, CONNECTICUT, A CORPORATION OF CONNECTICUT.

TYPE-WRITING MACHINE.

1,252,382.

Specification of Letters Patent.

Patented Jan. 8, 1918.

Application filed June 12, 1914. Serial No. 844,652.

To all whom it may concern:

Be it known that I, NILS H. ANDERSON, a citizen of the United States, residing at Middletown, in the county of Middlesex 5 and State of Connecticut, have invented certain new and useful Improvements in Type-Writing Machines, of which the following is a full, clear, and exact description, such as will enable others skilled in the art to which it appertains to make and use the same.

This invention relates to typewriting machines, and with regard to certain more specific features thereof, to the mechanisms 15 and associated parts designed to control the movement of the escapement rocker for permitting a letter-feed movement of the platen carriage.

One of the objects of the present invention is to provide a simple and practical arrangement of parts for efficiently and silently controlling the movement of the escapement rocker under varying conditions of operation. A further object is to 20 provide a mechanism of the above character having a desirable and uniform touch. A further object is to provide a mechanism of the first above-mentioned character which will be inexpensive to manufacture 25 and easy to assemble. A further object is to provide practical means of so mounting the parts as to permit ready adjustment, to enhance their ease of movement and to reduce wear. Other objects will be in part 30 obvious and in part pointed out herein-after.

The invention accordingly consists in the features of construction, combinations of elements and arrangement of parts which 40 will be exemplified in the construction hereinafter set forth, and the scope of the application of which will be indicated in the following claims.

In the accompanying drawings, in which 45 is illustrated one of the various possible embodiments of the several features of the invention,—

Figure 1 is a side elevation of the complete device showing such parts of a type-writing machine as are necessary to understand the present invention;

Fig. 2 is a front elevation, partly in section, showing certain features of the present invention;

Fig. 3 is an enlarged detailed plan view 55 of the parts shown in Fig. 1, certain parts being broken away, removed or shown in section, in order that the invention may be more clearly understood;

Fig. 4 is an enlarged detail perspective 60 view;

Fig. 5 is a rear view of the escapement rocker;

Fig. 6 is a detail view, partly in section, 65 of a connecting clip; and

Fig. 7 is a detail view, partly in section, 70 of a connection between the rocker member and actuating link.

Similar reference characters refer to similar parts throughout the different views 75 of the drawings.

For convenience, the present invention will be hereinafter described with relation to the Noiseless typewriting machine, with which it is particularly adapted to be used. 75 This machine, like other practical, commercial machines in general use, is provided with a longitudinally movable carriage having a letter-feed movement from right to left, with the platen of which the type 80 are adapted to coat at each letter-feed movement thereof, in order to produce the printed line. This movement of the carriage is controlled by suitable escapement mechanism positioned in the lower rear 85 part of the machine and connected with the carriage by intervening parts of any desired form to accomplish the desired result. As these parts, including the escapement shaft, for example, and their functions are broadly well known to those familiar with the art, they are herein only briefly referred to, as may be suggested in the interest of amplification of the disclosure. 90

Referring now to the drawings, and more particularly to Fig. 1, the side walls 1 of the frame of the machine are connected by a transverse supporting member 2 from which is suspended the escapement bracket 100 3 carrying an escapement wheel 4 at the lower end of a shaft 5. The upper end of

the shaft 5 is provided with the usual rack and pinion mechanism (not shown) for controlling the letter-space movement of the carriage, as above explained. Escapement mechanism 6, mounted upon a suitable rocker 7, coacts with the teeth of the escapement wheel 4 at each intermittent action of any type action, or the space-bar. This rocker member 7 is connected by mechanism, now about to be described in detail, with a space-bar 8 located in the front of the machine adjacent the keyboard, or with the universal bar 9 positioned beneath the key levers 10, as shown in Fig. 1, in such a manner as to permit independent operation thereof; that is, the key levers 10 may be depressed to actuate the universal bar 9 and the escapement rocker 7 independently of the space-bar key 8, and vice versa.

Taking up the construction of the rocker member and its associated connecting parts first, the escapement rocker is mounted on anti-friction bearings 11 and carries at its forward end escapement dogs (not shown in Fig. 3) for coacting with the escapement wheel 4. The escapement rocker 7 is provided with two downward extending arms 12 and 13, one at each side, loosely connected with the space-bar mechanism through one side and the universal bar mechanism through the other, by suitable slotted links 14 and 15, respectively. At the upper part of the escapement bracket 3 is positioned an auxiliary sheet-metal bracket 18 for the purpose of carrying various adjusting means for controlling the tuning of the escapement. To adjust the normal or inactive position of the rocker an adjusting screw 19 is provided in the lower part of the rocker, which screw is checked in place by suitable lock nut 20. The point of this screw 19 is adapted to engage in the lower ear of the auxiliary bracket 18 and its adjustment in or out controls the initial position of the escapement dogs in relation to the teeth of the escapement wheel, the entire escapement rocker being held in normal position by the action of an escapement adjusting spring 21 which is securely fastened to the escapement rocker at its lower end, and is provided at its upper end with a roller 22 bearing on an enlarged plate on the end of an adjusting screw 23 carried by the upper ear of the auxiliary bracket 18. A check nut 24 is provided for holding the parts in adjusted position.

When a key lever is depressed in operation with the consequent downward movement of the universal bar, the link 15 moves forward, but does not actuate the rocker member 7 until the lost motion of a longitudinal slot at its rear end is taken up by positive engagement of an adjusting screw 17 with a headed screw (similar to 62, Fig. 7) on the arm 13. By adjusting this screw 17 in or out it is thus possible to time the

point of pick-up of the escapement rocker with the type bar, or with the time of printing. The amount of movement which must take place in the rocker member before the escapement is tripped is controlled by the adjustment of the adjusting screw 19. After the printing has been effected, the reverse action takes place, the escapement rocker rotates with the rearward movement of the link 15 until the stop screw 19 comes in contact with the bracket 18. At this point the movement of the escapement rocker ends; that is, it has been returned to its normal or initial position, and continued movement of link 15 is permissible by the slot in end portion of link 15, allowing the universal bar 9 to return to its normal position. It is understood that in normal position of the various parts the stop screw 17 is not in contact with screw corresponding with abutment screw 62 in Fig. 7. If stop screw 17 normally contacted with the abutment of arm 13, an objectionable clicking would be caused when the escapement returned to normal position after actuation by the space bar. In other words, both connection 15 and connection 14 have a slight forward movement previous to engaging the abutment on arms 12 and 13 and consequently do not move the escapement rocker until a slight forward movement of the links 14 and 15 has taken place.

The escapement adjusting spring 21 tends to constantly rotate the escapement rocker 7, and since the link 15 is connected to the universal bar which moves with the key levers and type actions, the adjustment of this tension spring allows of setting the tension in such a manner that any desired touch may be had on the keys in the keyboard of the machine. This spring 21 is not in operation during the first part of the stroke or prior to the printing moment, and, therefore, introduces just at that moment a spring tension of considerable force in addition to that normally and constantly had from the universal bar spring. The actual effect of this is to put into the type action a feeling of life, which is desirable in getting the proper touch. Thus, a very light initial touch is secured on the keyboard, and it is only when the type actions have acquired the accelerated motion and momentum, that the escapement mechanism is picked up and actuated.

To a front transverse brace 30 in the frame of the machine are fastened brackets 31 provided with pivot screws 32 forming bearings for the universal rock shaft 33. Arms 34 and 35 are secured one at each end to this shaft, and their opposite ends are secured to universal bar 9 extending below the key levers transversely of the machine. This universal bar is made up of a felt pad, set securely in a channel bar, as clearly shown in Fig. 4. To the universal rock shaft 33 is

also secured an arm 36 to which is pivotally connected the link or pull wire 15, which in turn is connected at its opposite end to the escapement rocker, as above explained.

5 It will be seen, therefore, that pressing any key lever, such as 10, it will rock or tend to force the universal bar 9 positioned therebelow, downward, thus rotating the universal rock shaft 33 and moving the link 15 forward toward the keyboard. This, in turn, causes the escapement rocker 7 to be thrown upward into its active position. A release of the key levers permits the parts to complete their cycle of operation and return to 15 normal inactive position.

The mechanism for actuating the escapement rocker from the space bar or key 8 independently of the universal bar includes the space bar positioned at the front of the 20 machine and usually below and in front of the keyboard. This bar is fastened to the forward ends of arms 40 assembled upon a rock shaft 41 mounted upon suitable adjustable pivots 42 near each end. These pivots 25 are preferably in the form of pivot screws provided with check nuts 43, as shown, and are mounted in brackets 44 assembled on the cross brace 30 of the frame of the machine.

An upwardly extending arm 46 is also 30 mounted upon the rock shaft 41 and is fastened permanently thereto by means of a taper pin, or the like, 47, and is connected at its upper end to the link 14 extending fore and aft of the machine.

35 A preferred form of connection for both the links 14 and 15 comprises a hardened stud riveted over at the end in the link and passing through a bushing 51 which is assembled fast on the upwardly projecting arm 46, as shown in Fig. 6. The stud at its outer end has a small pin or point 53 which is adapted to engage a hole in a clip 54, which clip is adapted to slide, by means of 40 its turned-over ears, on the link to engage 45 or disengage the point 53 in order to lock the link in engagement with the arm.

The tension or touch of the space bar may be adjusted by providing a return spring 55 which engages at one end a hole in the cross 50 bar 30 of the frame of the machine, and at its other end a hole in an adjustable collar 56 which may be rotated around the shaft 41 to secure any desired spring tension, after 55 which it is locked in place by means of a set screw 57.

The link 14 extends toward the rear of the machine and engages the downwardly projecting arm 12 on the rocker member, as clearly shown in Fig. 1. The actual connection 60 comprises a separate member 58 secured to the end of the link 14 provided with a slot and offset end 59 carrying an adjusting screw 60 and lock nut 61. A shouldered screw 62 secured to the downwardly extending arm 12 of the rocker member passes

loosely through this slot and the amount of lost motion therein is controlled by the position of the adjusting screw 60, being similar to the connection of the link 15 on the opposite side.

70 When the key levers of the machine are being used in contradistinction to the operation of the space bar, the escapement mechanism is connected therewith through the universal bar 9 and intervening link 15, as previously described, the escapement rocker completing its cycle of operation to give a regular intermittent letter-feed movement to the carriage. Under these conditions of operation, the shouldered screw 62 which is 75 in the lower end of the rocker arm 12 slides back and forth in the slot provided at the end of the link 14 connecting the rocker with the space bar mechanism, thus allowing movement of the escapement rocker without 80 movement of the space bar mechanism. When the space bar, however, is operated, this link 14 moves forwardly until the point of the adjusting screw 60 engages the head of the screw 62 in the lower part of the 85 rocker arm 12, when the escapement rocker is operatively connected and actuated. During this operation, however, the connection at the lower end of the opposite escapement rocker arm 13 and the link 15 connecting 90 it with the universal bar mechanism permits a similar lost motion to take place, thereby eliminating any movement of the 95 universal bar mechanism.

This mechanism provides means by which 100 the space bar can be actuated without movement of the universal bar, and also provides means by which the space bar mechanism may be timed to actuate the escapement at any desired point; that is, a longer or 105 shorter dip of the space bar before tripping the escapement by adjusting the screw 60 passing through the turned-over end 59 of the connecting link 14. This is of great advantage, since there is some difference of 110 opinion between operators as to a desirable space bar action, some operators preferring the longer dip and other operators preferring a very short dip with great sensitiveness of adjustment.

115 In order to stop the downward movement of the space bar 8 after the adjustment of the screw 60, suitable stops 65 are provided under the space bar, for each of which there is an adjusting screw 66 provided at its top 120 with a pad of felt or some other resilient silencing means checked in place with a nut 67. The up or return movement of the space bar is stopped by positioning upon the under side of the space bar a plate 70 125 having a downwardly projecting stud 71 which passes through a relatively large hole in a second plate 72 mounted on the frame of the machine and held in place by check nuts 67 threaded upon the screw portions 130

66 of the silencing pads limiting the downward movement of the space bar. This stud 71 is threaded at its lower end, and carries two knurled nuts 73 and 74, one of which 5 is adapted to act as a lock for the other when placed in properly adjusted position. Between the nut 74 and the plate 72 limiting its upward movement is positioned a felt washer 75 for the purpose of eliminating 10 any noise at this point.

The upward or normal position of the space bar is stopped and regulated by the adjustment of these nuts. Since the stop for the bar is near the bar itself rather than 15 close to the pivot or shaft upon which it turns, there is little or no tendency for rebound. The structure, furthermore, provides a means for adjusting the normal position of the space bar in correct relation to 20 the keyboard.

In order to provide a silent action for the universal bar, as well as to provide a more desirable touch for the key levers, there is provided, in the central part of the machine, a universal bar stop, as shown more clearly in Figs. 1 and 3, designed to retard as little as possible the initial downward movement of the universal bar, yet afford at the same time a cushion at the end of the 25 stroke which, incidentally, aids in the initial return or the upward movement of the universal bar. The present structure is designed to eliminate the friction and drag upon the universal bar producing a more or 30 less sluggish action. The universal bar, as above explained, is carried on suitable arms 34 and 35, mounted upon the universal rock shaft 33 and is adapted to coact with a bell crank lever 80 mounted upon a stud 81 and 35 connected at its short end 82 with a spiral spring 83 adjustably connected at its opposite end to a relatively fixed portion of the frame of the machine, by adjusting screw 84 provided with a suitable form of check 40 nut 85. At the upper portion of the bell crank lever is a bent ear 86 which is adapted 45 to engage another oppositely bent ear 87 on a second bell crank lever 89, which is also spring-controlled by a spring 90, adjustably mounted at 91, similar to the spring 50 83 above mentioned, but of heavier tension. Both bell crank levers are carried by a bracket 92 attached to the frame of the machine. The normal or initial position of the bell crank lever 89 under tension of 55 its spring 90 is controlled by an adjusting screw 93 and nut 94 passing through an ear 95 on the lever 89 and engaging the bracket 92. In operation, the spring 83 is only of 60 sufficient tension to afford a prompt return of the universal bar, and as the bell crank lever 80 is moved downward under the action of the universal bar, on approaching the end of its stroke or movement the ear 65 86 of the bell crank lever engages the cor-

responding ear 87 on the adjacent bell crank lever, thereby tensioning the heavier spring 90 attached to the latter. Additional spring resistance is thus introduced at the end of the stroke, not only giving a cushioning 70 effect or feel in the key lever, but also giving a rapid initial kick back or upward return movement to the universal bar. The point at which this heavier spring tension is introduced or picked up by the bell crank 75 lever is adjustable through the adjusting screw 93 above mentioned.

As shown more clearly in Fig. 3, the bell crank levers 80 and 89 are mounted on bushings 96 to afford a proper bearing on the 80 studs supporting them and are retained in place by spring wire collars 97. The full downward movement of the universal bar is arrested by the stop or cushion 98 having an adjustable but normally fixed relation to 85 the frame of the machine. In actual practice these stops are not always engaged by the universal bar, as the tension of the heavier spring attached to the bell crank lever is sufficient to afford a satisfactory 90 stop.

As the operation and method of use of this complete device are believed to be clear from the above description, a further explanation thereof is believed to be unnecessary. It will be clear that the escapement rocker is actuated independently by either the key levers or the space bar, both of which are provided with silencing means which not only permits a noiseless action, 100 but contributes materially to the efficiency of the machine in providing a desirable touch to all of the finger-actuated parts.

The various elements entering into the combination are so positioned and arranged 105 and connected with each other as to permit the parts to be rapidly assembled at a low cost of manufacture. In short, the invention is believed to accomplish, among others, all of the objects and advantages above set 110 forth.

As many changes could be made in the above construction and many apparently widely different embodiments of this invention could be made without departing 115 from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, in combination, an escapement rocker having a pair of 120 spaced arms, a pair of fore and aft links having independent lost-motion connections with said arms respectively, and independent bell crank connections between said links and the universal bar and the space bar. 125 130

2. In a typewriting machine, in combination, a horizontally disposed escapement rocker having depending arms, a pair of fore and aft links having independent lost-motion connections with said arms respectively, independent bell crank connections between said links and the universal bar and the space bar, independent means urging said links to normal position, and means for controlling the normal position of said rocker independently of said first-mentioned means.
3. In a typewriting machine, in combination, an escapement rocker, a fore and aft link having one end connected thereto, a transverse rock-shaft adjacent the other end of said link, an arm on said rock-shaft having a pivotal connection with said last-mentioned end of said link, a pair of spaced fore and aft arms on said rock-shaft having a space bar at their forward ends, and a coil spring about said rock-shaft for returning the same when actuated.
4. In a typewriting machine, in combination, an escapement rocker, a universal bar, connections between the universal bar and the rocker, and a stop for the universal bar, comprising a bracket and a pair of levers mounted thereon having a lost-motion device therebetween, one of said levers being operable by the universal bar to actuate the other after the universal bar has been depressed a predetermined amount.
5. In a typewriting machine, in combination, an escapement rocker, a universal bar, connections between the universal bar and the rocker, and a stop for the universal bar, comprising a bracket, a pair of levers mounted thereon having a lost-motion device therebetween, one of said levers being operable by the universal bar to actuate the other after the universal bar has been depressed a predetermined amount and a spring opposing actuation of said other lever.
6. In a typewriting machine, in combination, an escapement rocker, a universal bar, connections between the universal bar and the rocker, and a stop for the universal bar, comprising a bracket, a pair of bell crank levers mounted thereon having a lost-motion device therebetween, one of said bell crank levers being operable by the universal bar to actuate the other after the universal bar has been depressed a predetermined amount, a spring coacting with said second-mentioned bell crank lever adapted to be actuated after the bell crank has been engaged by the first bell crank lever and means for regulating the tension of the spring.
7. In a typewriting machine, in combination, an escapement rocker, a universal bar, connections between the universal bar and the rocker, and a stop for the universal bar, comprising a T-shaped bracket, a lever mounted upon each side of said bracket and having an ear bent toward the other, one of said levers being adapted to coact with said universal bar and be moved thereby until its ear coacts with the ear of said second lever, and a spring connected with said second lever adapted to be tensioned after said ears are moved into contact.
8. In a typewriting machine, in combination, an escapement rocker, a universal bar, connections between the universal bar and the rocker, and a stop for the universal bar, comprising a bracket, a pair of movable members mounted thereon, a spring connected with each of said members, one of said members being connected with the universal bar for actuation thereby, and a lost-motion device between said members adapted to cause a movement of the second member after said first member has been moved a predetermined distance.
9. In a typewriting machine, in combination, an escapement rocker, a universal bar, an operative connection therebetween, resilient means tending to oppose and limit actuation of said universal bar with a varying force abruptly augmented adjacent the limit of movement of the latter, and means for regulating the augmentation of said force without varying the period of augmentation.
10. In a typewriting machine, in combination, an escapement rocker, a universal bar, an operative connection therebetween, resilient means tending to oppose and limit actuation of said universal bar with a varying force abruptly augmented during the final movement of the latter, and means for varying the period of augmentation of said force.
11. In a typewriting machine, in combination, an escapement rocker, a universal bar, an operative connection therebetween, resilient means tending to oppose and limit actuation of said universal bar with a varying force abruptly augmented during the final movement of the latter, and means for varying the period and amount of augmentation of said force.
12. In a typewriting machine, in combination, an escapement rocker, a universal bar, an operative connection therebetween, resilient means tending to oppose and limit actuation of said universal bar with a varying force abruptly augmented during the final movement of the latter, and means for varying independently the amount of said force during the period prior to and after augmentation thereof.
13. In a typewriting machine, in combination, escapement mechanism, a space bar, intervening mechanism for transmitting motion from one to the other, a stop for said space bar comprising a bracket secured to the frame of the machine, a member mounted on said space bar passing through said

bracket, and means associated with said member for limiting the return movement of said space bar.

14. In a typewriting machine, in combination, escapement mechanism, a space bar, intervening mechanism for transmitting motion from one to the other, a stop for said space bar comprising a bracket secured to the frame of the machine, a member mount-

ed on said space bar passing through said bracket, and means adjustably mounted on said member adapted to limit its movement.

In testimony whereof I affix my signature, in the presence of two witnesses,

NILS H. ANDERSON.
